UNITED STATES PATENT OFFICE.

ALBERT E. HUDSON, OF BEVERLY, AND WILLIAM C. WILLSON, OF MEDFORD, MASSACHUSETTS, ASSIGNORS TO UNITED SHOE MACHINERY CORPORATION, OF PATERSON, NEW JERSEY, A CORPORATION OF NEW JERSEY.

METHOD OF AND MACHINE FOR COMPRESSING BOOT AND SHOE PARTS.

Application filed December 19, 1919. Serial No. 346,095.

To all whom it may concern:

- Be it known that we, ALBERT E. HUDSON and WILLIAM C. WILLSON, citizens of the United States, residing at Beverly, in the county of Essex and State of Massachusetts, and Medford, in the county of Middlesex and State of Massachusetts, respectively, have invented certain Improvements in Methods of and Machines for Compressing 5 Boot and Shoe Parts, of which the following description, in connection with the accompanying drawings, is a specification, like reference characters on the drawings indicating like parts in the several figures.
- 10 This invention relates to a method of and machine for compressing boot and shoe parts, such, for instance, as heel parts, top lifts, and the like. The advantages and results of the invention are more particularly 15 observable in the compression of top lifts of heels for boots and shoes, and, therefore, the invention will be herein described as applied for this purpose. It is to be understood, however, that the invention may be advantageously employed for compressing other 20 boot and shoe blanks and, consequently, is not restricted to compressing or condensing top lifts.
- The top lifts of boot and shoe heels come 25 directly in contact with the ground when the boot or shoe is on the foot of the wearer and it is now the common practice to subject top lifts to a heavy condensing pressure in suitable molds before they are applied to 30 the heels of boots and shoes, in order to consolidate the material of the top lifts and thereby increase their wear resisting qualities. In order to condense and permanently set the fibres of the top lifts, the pressure exerted upon the material of the top lifts is 35 now effected between two opposed rigid compressing members. A machine of this general character is shown and described in the United States patent to Thomas Lund No. 40 1,172,471, dated September 22, 1916, and the product of the patented machine is of superior quality, and the machine itself has been commercially successful. Its output, however, has been limited to the capacity of the
- 45

machine which is intended to treat one blank 50 or top lift at a time.

The constantly increasing use of compressed top lifts, however, has created a demand for greater quantitative product without at the same time sacrificing the quality 55 of the product, which depends upon the character and effect of the pressure upon the fibrous structure of the top lift materials.

An important feature of the present invention, therefore, consists in a method of 60 assembling a plurality of heel lifts in alternating relation with presser plates to form a composite pile and then subjecting the composite pile of lifts and plates to a lift condensing pressure. 65

In carrying this feature of the invention into effect, suitable means may be employed for assembling the lifts and presser plates into piles composed of alternating lifts and plates, and likewise any suitable compressing mechanism may be employed for exerting the desired condensing pressure on the composite pile of lifts and plates. Since the lifts or shoe blanks which are to be subjected to compression in the pile of alternating blanks and plates, are in surface contact with the substantially rigid presser plates, the condensing pressure applied to the composite pile is transmitted with substantial uniformity to all of the lifts or 70 blanks in the pile and uniform product of high quality and increased production results. 75

In order that the simultaneous production of a plurality of condensed lifts may be effected through the action of compression members applied to composite piles of lifts and presser plates, the present invention includes, in addition to the method hereinbefore announced, a machine of novel construction and operation for carrying the method into effect. 85

An important feature of the present invention in this respect consists of means for taking top lifts and presser plates from 90 sources of supply and arranging them into a pile in which a presser plate is interposed between each of the adjacent lifts, and means 95

for subjecting the composite pile to a top lift condensing pressure.

This feature of the invention, in the present instance, is carried into effect by arranging a series of heel lift magazines and presser plate supplying means adjacent to an assembling mechanism to which the heel lifts and presser plates are delivered in alternating relation to form composite piles 10 of lifts and plates.

When a composite pile of lifts and presser plates has been completed at the assembling station, the invention intends that it shall be delivered to a compression station for 15 condensing the pile. An important feature of the invention in this respect, therefore, consists of means for transferring a composite pile of heel lifts and presser plates to means for subjecting the composite pile to 20 the condensing pressure.

After the composite pile of heel lifts and presser plates has been subject to the action of the pressure means, the now condensed heel lifts and the presser plates must be 25 separated, and another important feature of the invention, therefore, consists of means for separating the condensed heel lifts and presser plates after the treatment of a composite pile of lifts and plates by the pressure means.

The presser plates are preferably of substantially rigid metallic material, and are susceptible of repeated use in the machine. Another important feature of the invention, 35 therefore, consists in returning the presser plates to the sources of supply adjacent the assembling mechanism where such presser plates are separated from the previously associated condensed heel lifts.

40 Other important features of the invention, and novel combinations of parts, in addition to the above, will be hereinafter described in connection with one good practical form or mechanical embodiment thereof, 45 but it is to be understood that the invention is not restricted to the particular details which may be varied within the true scope of the present invention which is definitely described by the claims.

50 In the drawings:

Fig. 1 is a plan view of a machine for treating top lifts for the heels of boots and shoes in accordance with the present invention;

55 Fig. 2 is a side elevation and part sectional view showing more particularly one good form of compression mechanism and its associated parts;

Fig. 3 is an enlarged side elevation of 60 portions of the assembling mechanism and sources of supply for the heel lifts and presser plates, certain parts being broken away and exaggerated to avoid complication of the drawings;

65 Fig. 4 is a detached detail on an enlarged

scale showing one good form of means for insuring the separation of the condensed lifts and the presser plates after the composite pile has been subjected to condensing pressure;

70 Fig. 5 is a section on the line 5—5 of Fig. 3 showing the general form of the chute for returning the presser plates to the machine for further use;

Fig. 6 is an enlarged sectional view on the 75 line 6—6 of Fig. 1 showing more particularly the means for delivering the heel lifts and presser plates to the assembling mechanism;

Fig. 7 is an enlarged sectional view on the 80 line 7—7 of Fig. 3 showing the means for transferring a composite pile of heel lifts and plates from the assembling station to the compression mechanism;

Fig. 8 is an enlarged sectional detail 85 through a portion of the carrier or turret showing the means for progressively separating the alternate condensed lifts and plates, one at a time; and

Fig. 9 is an enlarged plan view showing 90 details of the mechanism illustrated in Fig. 8.

The machine frame may be of suitable form and character for supporting the operating parts, and in the present instance, 95 comprises a table or support 1 at the heel lift and presser plate assembling station, and a frame 2 which may constitute a support for the carrier which transfers the piles of heel lifts and presser plates to the 100 compression mechanism and then to the discharging stations.

The machine frame 2 has an extension 3 in which is mounted the driving shaft 4 carrying the fast and loose pulleys 5 and 6, 105 Fig. 2, which may be actuated by suitable driving means, such, for instance, as belting from a line shaft. The driving shaft 4 carries the gear 7 which meshes with a pinion 8 mounted on the shaft 9 on which is secured the gear 10 which transmits motion to the main driver 11 mounted in suitable bearings 12 carried by the extensions 3 of the machine frame 2. The main driver 11 is secured to the shaft 13 which has connected thereto the crank disk 14. A rod 15 connects the crank disk 14 with the crank arm 16 by which oscillatory motion is transmitted to the shaft 17 shown in full lines, Fig. 2, and in dotted lines, Fig. 1. The 110 shaft 17 is operatively connected to the shaft 18, Figs. 1 and 2, which may be supported in suitable bearings 19 carried by the bracket 20 secured to the machine frame 2, as indicated in Figs. 1 and 2.

115 From the construction thus far described it will be seen that rotary movement imparted to the main shaft 4 is transmitted through the train of mechanism described, 120 into oscillatory movement to the shaft 18, 130

and such oscillatory movement is utilized in the present instance of the invention to transmit motion to the heel lift and presser plate feeding means and impart to the assembling mechanism a step by step movement in one direction, as will more fully appear.

Secured to the oscillating shaft 18 is a bevel pinion 21 Fig. 1, which meshes with a corresponding pinion 22 on a shaft 23 which, in turn, is connected to the presser plate feed shaft 24, Fig. 1, through a suitable train of mechanism which, in the present instance of the invention, consists of a sprocket wheel 25 on the shaft 24, and a sprocket and chain connection 27 and 26.

The shaft 23 has imparted thereto the oscillatory movement of the shaft 18 and advantage is taken of this movement of the shaft 23 to transmit to the heel lift feed shaft 28 its oscillatory rotary movement. The train of gearing between the shaft 23 and the feed shaft 28 is indicated by dotted lines in Fig. 1 wherein the shaft 23 is shown as provided with the pinion 29 which engages with a toothed wheel 30 mounted on the counter shaft 31 from which motion is directly transmitted to the feed shaft 28 by a sprocket chain connection 32, Fig. 1, the construction being such that the feed shafts 24 and 28 will be given an oscillatory rotary movement for feeding the heel lifts and presser plates to the assembling mechanism.

Mounted on the table 1 adjacent the assembling mechanism, presently to be described, is a series of heel lift magazines 33 which may be of suitable number to provide separate series of stacks of heel lifts. In the present instance of the invention, three heel lift magazines are indicated, but it is to be understood, of course, that the number may be varied to correspond to the number of heel lifts that are to be comprised in each of the composite piles of heel lifts and presser plates.

The heel lift magazines 33, as best indicated in Fig. 3, may be supported from the table 1 by means of the brackets 34 to which the lower portions of the magazines may be adjustably attached.

Adjacent the series of magazines for holding the stacks of heel lifts, is the heel lift and presser plate assembling mechanism, which, in the present instance of the invention, comprises the sprocket chains 35 and 36 which pass over the sprocket wheels 37 and 38 rotatably mounted in suitable hangers 39, Fig. 3, depending from or supported by the table 1. The sprocket chains 35 and 36 have extending between them the finger plates 40, the lower edge portions of which travel along the support 41 which is adapted to have placed upon it in front of the finger plates 40, the composite piles of heel lifts and presser plates, the construction being

such that the composite piles are supported upon the support 41 and are progressively moved along said support by the assembling mechanism or conveyor which is constituted by the sprocket chains and finger plates. 70

The assembling mechanism is given a step-by-step or intermittent movement longitudinally along the support 41. This may be effected by a suitable train of mechanism connected to the oscillating shaft 18. In the present instance the shaft 18 has loosely mounted thereon the sprocket wheel 42, Fig. 1, the outer surface of which is constituted as one part of a clutch, the other part 43 of which is mounted for rotative movement with the shaft 18 and is held in operative engagement with the opposing clutch member by a spring 44, the construction being such that when the shaft 18 is oscillated in one direction it will turn the sprocket wheel 42 through the clutch connection described and when it is oscillated in the opposite direction, the sprocket wheel 42 will remain at rest. Mounted upon a bracket 45 secured to the machine frame 2 is the shaft 46 on 90 which is secured the sprocket wheel 47 connected by a sprocket chain 48 with the sprocket wheel 42. Mounted on the shaft 46 to rotate with the sprocket wheel 47 is a bevel gear 49, Fig. 1, which meshes with a correspondingly beveled gear 50 on the shaft 51 which carries the sprocket wheels 38 about which the sprocket chains 35 and 36 travel, the construction being such that the sprocket chains 35 and 36 and finger plates 95 constituting the assembling mechanism, will be given a step-by-step progressive movement to carry the heel lifts and presser plates along the support 41. 100

The present invention, as hereinbefore indicated, provides for forming piles of heel lifts with presser plates arranged between adjacent lifts, and in order that the condensing pressure which is to condense and set the fibrous material of the heel lifts, may be transmitted with substantially undiminished pressure, throughout the series of heel lifts in the pile, such presser plates are substantially rigid or unyielding, and means is provided for alternately feeding a heel lift and a presser plate to the composite piles to be compressed. 110

In the present instance of the invention the presser plates are formed of metal and are sufficiently heavy to prevent flexure of the presser plates during compression. 120

Mounted in alternating relation with the heel lift magazines are the presser plate sources of supply which, in the present instance, are constituted by chutes 52 and 53, two of them being shown in the present illustration of the invention, but the number may be varied to correspond with the number of magazines for the heel lifts. As will presently be described, the presser plates are 130

supplied to the chutes 52 and 53 from the composite piles of heel lifts and press plates after such piles have been compressed and are positioned at the lower ends of the 5 chutes 52 and 53 by suitable stops 54, Figs. 1 and 6. These stops may be adjustably connected to the table 1 by means of the bolts 55 which pass through slots in the supporting portion of the stops.

- 10 Since the heel lifts and the presser plates are to be arranged in piles of alternating lifts and plates, the magazines and presser plate supplies are alternately arranged as indicated in Fig. 1, wherein the magazines 15 for the heel lifts and the source of supplies for the presser plates, are shown as disposed on opposite sides of the path of movement of the assembling mechanism and are fed thereto through means connected to the 20 feed shafts 24 and 28, respectively.

Secured to the feed shaft 28, as best illustrated in Fig. 6, is a pinion 56 which meshes with a toothed rack 57 mounted for sliding movement in the ways 58 in the table 1 at 25 one side of the path of movement of the assembling mechanism. The rack 57 has connected thereto the pusher 59, the active end portion of which is provided with a recess 60 into which the lower lift *a* of the 30 adjacent stack of lifts may rest when the rack is in its non-feeding or withdrawn position. When the pusher 59 is moved to feed the lowermost lift of the stack to the support 41, the upper surface of the pusher 35 59 moves under the superposed lifts and supports the upper lifts of the pile as the lowermost lift is fed to the support.

Mounted upon the presser plate feed shaft 24, Fig. 6, is a pinion 61 the teeth of which 40 engage the teeth of a rack 62 mounted for sliding movement in the way 63 formed in the table 1, substantially similar to the feed rack for the lifts hereinbefore described. Secured to the rack 62 is the pusher 64, the 45 leading end portion of which is recessed at 65 to receive the presser plate *b*, Fig. 6, and the pusher 64 is provided with the lugs 66 which engage the trailing side of the presser plate *b* and maintain it in proper position 50 to be superposed upon a heel lift previously moved onto the support 41. In order to insure that the presser plate *b* shall be detached from the pusher when the latter moves the plate over the previously positioned lift, a finger 67, preferably of spring 55 nature, has its leading end 68 positioned to engage the trailing edge of the lift and detach it from the pusher as the latter is withdrawn. The finger 66 may be held in position 60 by a bridge piece 69 extending from the stop 54, Fig. 6.

When the assembling mechanism is at rest between its intermittent movements, the pushers for the heel lifts and presser plates 65 are actuated to simultaneously transfer from

the magazines and the presser plate supplies, a series of lifts and plates sufficient in number to complete a composite pile of lifts and plates, and owing to the alternate arrangement of the magazines and plate supplies, and the intermittent movement of the assembling mechanism, the heel lifts and presser plates will be arranged in piles of alternate heel lifts and plates, and the leading pile will be completed on each reciprocating movement of the pushers after the machine has been in operation. 70 75

In the illustrated form of the invention, the support 41 is shown as a horizontal surface on which the piles of lifts and plates 80 are formed as the assembling mechanism intermittently moves the piles along the support, consequently the pushers for the heel lifts and presser plates are arranged in progressively higher planes, as indicated in 85 Fig. 3; that is, the pusher for the first magazine of the series, shown at the right, Fig. 3, is the lowest of the series of pushers and moves a heel lift from the adjacent 90 magazine directly onto the support 41. The pusher for the presser plate which is next in order to be transferred to the assembling mechanism, is sufficiently higher than the pusher for the heel lift to transfer a presser plate onto that lift when it reaches 95 the plate feeding station. The pusher for the second magazine is higher than the pusher for the first inserted presser plate in order to deliver a heel lift onto the presser plate when the pile reaches the feeding position for the second lift, and so on throughout the series substantially as indicated in 100 Fig. 3.

A composite pile of heel lifts and presser plates having been completed, as indicated 105 at the left, Fig. 3, it is to be transferred to the pressure mechanism for receiving the condensing pressure which may be applied by any suitable form of compression mechanism as, for instance, that shown and described in the patent to Thomas Lund, No. 1,172,471, dated February 22, 1916. 110

The transerrer may be variously devised, but in the present instance of the invention, as indicated in Figs. 3 and 7, it comprises a 115 lifting head 70 having a downwardly extending stem 71 which is received in a plunger 72 having rack teeth at one portion thereof, as at 73, which engage the teeth of a gear or pinion 74 mounted on a shaft 75 120 which receives its motion intermittently through a train of mechanism connected to the shaft 31, Fig. 1. In the present instance, the shaft 31 is extended to the left, Fig. 1, and carries a sprocket wheel 76 which is connected by a sprocket chain with a sprocket wheel 77 mounted on the short shaft 75 to which the gear or pinion 74 is secured, the construction being such that the head 70 will be raised at intervals to transfer a composite 125 130

pile of heel lifts and presser plates to a carrier by which the pile may be transferred to the compression mechanism. The support 41 adjacent the head 70, Fig. 7, is provided 5 with an opening through which the head 70 may pass to transfer the composite pile of lifts and presser plates to the carrier when such pile has been moved into position upon the head 70 by the finger plates of the assembling mechanism, as indicated in Fig. 3.

When the plunger 72 is in its lowered position, the top surface of the head 70 is in the same plane as the supporting surface of the table 41 and suitable stops 78 are 15 connected to the head 70 to insure proper coincidence of the top surface of the head 70 and the surface of the support 41. The stem 71 is provided with a pin 79 which extends into a recess 80 of the 20 plunger 72 and a spring 81 is interposed between the top of the plunger 72 and the head 70 for a purpose that will presently appear.

The compression mechanism is supported 25 upon the frame 2, hereinbefore described, and comprises a rigid abutment 82, Fig. 2, to which is secured the fixed die 83 constituting one of the pressure members. Mounted upon the frame 2 for rising and falling 30 movement relative thereto, is the presser head 84 which is given its rising and falling movements through the toggle levers 85 and 86, the member 85 of the toggle being pivoted at 87 to the head 84, and the lower end 35 of the member 86 of the toggle being pivoted at 88 to a fixed part of the frame. A link 89 is connected to the toggle at 90 and to a crank arm 91 carried by the shaft 13, Fig. 3, the construction being such that as the shaft 40 13 is rotated the toggle will be alternately straightened and broken to thereby raise and lower the head. The head is provided with dies 92 in which rests the top lift plate 93 having the stem 94 extending downwardly 45 therefrom to be engaged at times by a lifter 95, as more fully described in the patent to Lund hereinbefore mentioned, the construction being such that when the head 84 is raised, a composite pile of lifts and presser 50 plates will be taken from the carrier, to be presently described, and on further upward movement of the head the composite piles will be subjected to a condensing pressure. As the head 84 is moved downwardly, 55 the now compressed pile of lifts and plates will be moved upwardly by the ejector 95, as more clearly and fully described in the patent to Lund, and the pile of compressed lifts and plates will be transferred to the carrier, 60 as will more fully appear.

The carrier for taking the composite piles of lifts and plates from the transferrer and moving them into compressing position may be variously contrived, but in the 65 present instance of the invention it is formed

as a turret which comprises a bottom plate 96 which is fixed to the rising and falling head 84 and a rotary portion 97, Fig. 2, which is mounted upon the relatively fixed plate 96. The bottom plate 96 of the turret is provided with an opening 98, Fig. 1, which is located immediately above the transferrer head 70, the construction being such that when the transferrer head is moved upwardly to transfer a pile of lifts 70 and plates to the turret, the pile may be passed through the opening 98 in the fixed plate 96 and received into one of the corresponding openings 99 in the rotary turret 75 97, which, at the moment of transfer registers with the opening 98 in the relatively stationary bottom plate. The rotary turret 97 has a number of openings or socketed portions 99 which, in the present instance of the invention, are arranged in successive order, 80 as indicated in Fig. 1. The number of the openings 99 in the turret 97 may be varied, but in the present instance of the invention fourteen of these are indicated, the purpose being that as the turret is rotated, it 85 will carry a pile of composite lifts and plates from the receiving station above the opening 98 in the bottom plate 96 successively to the compression mechanism and after compression carry the series of compressed lifts 90 and plates to discharging stations, as will presently appear.

Rotary movement is imparted to the turret through a pinion 100, Fig. 1, which meshes with teeth 101 formed in the peripheral portion of the turret. The pinion 100 is mounted on a short shaft 102 carried by the bracket 103 mounted on the rising and falling head 84. The lower portion of the shaft 102 has secured thereto a clutch member 104 which is adapted to be actuated by a complementary clutch member 105 loosely mounted on the shaft 102 and provided with a bevel pinion 106, Fig. 2. A toothed rack or segment 107 is engaged with the bevel pinion 106 and mounted for rocking movement about an axis 108 by means of an arm 109 which is connected for lost motion to the upper end portion of a rod 110, the lower end of which is secured at 111 to the machine 105 frame 2, the construction being such that as the head 84 is raised to apply the condensing pressure to a pile of lifts and plates between the compression members, the turret 110 will not be rotated, the engaging teeth of the clutch members 104 and 105 at such times clicking past each other under the influence of a spring 112 which permits movement of the clutch member 104 longitudinally of the shaft 102 as the toothed segment 107 is oscillated. When, however, the head 84 is being lowered, the ejector 95 first acts through the stem 94 and top lift plate 93 to return the compressed pile of lifts and plates 115 to the opening in the turret from which 120 125 130

- they were removed for purposes of compression, and thereafter, due to the lost motion between the arm 109 and the actuating rod 110, the turret will be rotated to carry the 5 compressed pile of lifts and plates from between the compression members or dies, and substitute therefor another pile of lifts and plates to be compressed. It has not been considered necessary herein to enter into a 10 detailed description of all the features of the compression mechanism, since they may be of the same character as fully described in the patent to Lund hereinbefore mentioned.
- 15 It is appropriate at this time to refer to the function of the spring 81, Fig. 7, which yieldingly supports the transerrer head 70. As indicated in Fig. 1, the opening 98 in the fixed bottom plate of the turret and 20 the openings 99 in the turret itself, are of the general contour of the pile of lifts and plates with which they are to cooperate. Should a pile of lifts and plates contact with the bottom plate 96 as the transerrer moves 25 upwardly, the spring 81 will permit a yield and thus prevent breakage of parts. When the transerrer head has moved a pile of lifts and plates, through the opening 98 of the bottom plate 96, and into the registering opening 99 of the turret, it is desirable 30 that the top surface of the transerrer head 70 be substantially in the same plane as the top surface of the bottom plate 96. To insure this coincidence of the surfaces, the 35 stop 78 is provided on the transerrer head 70 to contact with the under surface of the plate 96 when the transerrer head has moved a pile of lifts and plates to the turret.
- 40 After a pile of lifts and plates has been subjected to the condensing pressure, the present invention proposes to separate the condensed lifts and plates and discharge them into different paths. In the present 45 instance, the turret 97 moves the condensed pile of lifts and plates from the compression mechanism by a progressive step-by-step movement and advantage is taken of this movement of the turret to separate the 50 condensed lifts and plates.
- The bottom plate 96 over which the turret moves, is provided with a series of discharge openings 113 over which a pile of condensed lifts and plates is moved after 55 the compressing operation. Each of the openings 113, except the last one in the series, at the left, Fig. 8, is provided with a door 114, and since these doors are all the same and are operated by similar mechanism, a description of one will be sufficient, and to this end attention is directed to Fig. 4 in which the door 114 is shown in its closed position. The door 114 is pivotally mounted on a supporting shaft 115 mounted 60 in suitable brackets 116 on the bottom plate 65
96. Fixed to and extending from the shaft 115 is a door operating finger 117, the upper end portion 118 of which is adapted to be engaged by the lugs 119 formed on the peripheral portion of the turret 97, when the turret is operated. The shaft 115, Figs. 4 and 9, is under the influence of a spring 120, preferably wound about the shaft 115 and acting therethrough to normally hold the door 114 in its closed position, as indicated in Fig. 4, but with permissive movement to be opened by the finger 117 when the latter is engaged by one of the lugs 119 during the rotary movement of the turret. The action of the spring 120 is limited by 80 an adjusting stop 121 against which the finger 117 abuts, as indicated in Figs. 4 and 9. As the turret 97 is rotated to position a pile of lifts and plates above one of the discharge openings in the bottom plate 96, 85 the pile of lifts, as indicated in Fig. 4, drops upon the door 114 which at the time closes the opening. The thickness of the door 114 is preferably such that when a top lift or plate rests upon the door, the surface contact between it and the superposed lift or plate is substantially in the plane of the upper surface of the bottom plate 96, so that as the turret is revolved, the superposed lifts and plates may be moved by the 90 turret, leaving the lower lift or plate resting upon the door. To prevent obstructing engagement of the leading end of the pile of lifts and plates as they are moved by the 95 turret from above the lower lift or plate, 100 as indicated in Fig. 4, the edges of the opening 113 are inclined or beveled, as indicated at 122.
- To insure that the condensed lift or plate resting upon the door 114 is discharged 105 when the door is opened by contact of one of the lugs 119 with the door opening finger 117, as the turret rotates, the present invention provides a kicker 123 associated with each of the openings 99 in the turret. The 110 kicker 123 is best indicated in Figs. 4 and 9 wherein it is shown as secured to a short shaft 124 mounted in suitable bearings 125 in the turret 97 adjacent the trailing wall of each of the recesses or openings 99. The 115 kicker 123 is under the influence of a spring 126 normally acting to throw the toe or free end of the kicker downwardly, but restrained from effecting such downward movement of the toe of the kicker by the 120 latter traveling upon the top surface of the bottom plate 96 as the turret rotates. When, however, the toe of the kicker 123 reaches the discharge opening 113 in the bottom plate, the kicker operating spring 126 throws 125 the end or toe of the kicker downwardly as it leaves the surface of the bottom plate. At this instant the door 114 has been opened into the dotted line position, as indicated in Fig. 4, with the result that the kicker hits 130

the condensed lift or presser plate and discharges it from the machine.

As the condensed lifts and plates are discharged, substantially in the manner hereinbefore described, they are directed into paths for collecting the lifts and for returning the presser plates to the feeding mechanism for further use. In the present invention, the discharge stations for the lifts and plates have associated therewith a conveyor. This conveyor may be variously devised, but in the present instance a separate conveyor is associated with each of the discharge openings 113 and when a lift or plate is discharged from the turret it is received upon the conveyor and conducted to the desired point. The conveyors for the plates have been hereinbefore referred to as the chutes 52 and 53, and the upper ends of these chutes, as indicated in Fig. 8, are positioned below the discharge openings and serve to receive the presser plates as they are removed from the turret. In order to return the presser plates to position for further use, the chutes 52 and 53 are formed inclined, as indicated in Fig. 3. These chutes may be formed as indicated by the cross section in Fig. 5, wherein the bottom portion 127 of each chute is concaved so as to offer little resistance to the travel of the substantially rigid presser plates down the inclined chutes. To prevent the presser plates jumping from the chutes as they move to the source of supply, each side is provided with the side flanges 128, Fig. 5. The upper end portions of the chutes, as indicated in Fig. 3, may be supported by suitable bracket arms 129 extending from the machine frame.

Below each of the lift discharge openings 113 is the upper end portion of the chute or conveyor 130 which, as the condensed lifts are discharged from the turret, as hereinbefore described, convey the lifts out of the machine.

Other forms of conveyors for the condensed lifts and plates might be employed within the present invention, but the chute form of conveyor is found to be effective for the desired purpose.

We claim—

1. The method of condensing top-lifts for boots and shoes, which consists in assembling a plurality of top-lifts and rigid presser plates of the same size and contour, respectively, into a pile with a rigid presser plate between adjacent top-lifts and then subjecting the composite pile to a top-lift condensing pressure.
2. The method of condensing a plurality of heel lifts which consists in forming a composite pile of heel lifts and substantially rigid presser plates of the same size and contour, respectively, in alternating relation, introducing the composite pile into an edge

confining mold, and then subjecting the composite pile to a lift condensing pressure to simultaneously condense and set the material of the plurality of lifts.

3. The method of simultaneously condensing a plurality of heel lifts which consists in forming a composite pile of dry, single heel lifts and rigid presser plates of substantially the same surface area as the lifts in alternating relation, and then subjecting the composite pile to a condensing pressure which is transmitted through the pile by the rigid presser plates.

4. The method of condensing a plurality of individual, dry heel lifts, which consists in forming a composite pile of said heel lifts and substantially rigid, flat presser plates in alternating relation, then subjecting the composite pile to a lift condensing pressure to simultaneously condense and set the material of the plurality of lifts, and then progressively separating the individual condensed lifts and presser plates.

5. In a machine for compressing top-lifts, the combination of means for taking a plurality of top-lifts and presser plates from sources of supply and arranging them into a pile in alternating relation, and means for subjecting the composite pile to a top-lift condensing pressure.

6. In a machine for compressing top-lifts, the combination of means for taking a plurality of top-lifts and presser plates from sources of supply and arranging them into a pile in alternating relation, means for subjecting the composite pile to a top-lift condensing pressure, and means for separating the lifts and plates after the top-lifts have been compressed.

7. In a machine for compressing top-lifts, the combination of means for taking a plurality of top-lifts and presser plates from sources of supply and arranging them into a pile in alternating relation, means for subjecting the composite pile to a top-lift condensing pressure, and means for transferring the composite pile to the pressure means for treatment.

8. In a machine of the class described, the combination of means for moving a series of heel lifts from sources of supply into alignment, means for moving a plurality of presser plates into alternating relation with the aligned series of lifts, and means for assembling lifts and plates alternately into piles.

9. In a machine of the class described, the combination of means for moving a series of heel lifts from sources of supply into alignment, means for moving a plurality of presser plates into alternating relation with the aligned series of lifts, and means for assembling the aligned lifts and plates with other lifts and plates to form piles of alternating lifts and plates.

10. In a machine of the class described, the combination of means for moving a series of heel lifts from sources of supply into alinement, means for moving a plurality of 5 presser plates into alternating relation with the alined series of lifts, means for assembling lifts and plates alternately into piles, and means for subjecting the assembled lifts and plates to a lift condensing pressure. 70
11. In a machine of the class described, the combination of means for holding a series of stacks of heel lifts, means for moving the bottom lifts from the several stacks into 10 positions from which they are to be assembled, means for moving a plurality of presser plates into positions alternating with the heel lifts, and assembling means for moving the positioned lifts and plates into 15 alternating relation with other lifts and plates. 75
12. In a machine of the class described, the combination of means for holding a series of stacks of heel lifts, means for moving the bottom lifts from the several stacks into 20 positions from which they are to be assembled, means for moving a plurality of presser plates into positions alternating with the heel lifts, assembling means for moving the positioned lifts and plates into 25 alternating relation with other lifts and plates, and means for subjecting the alternating lifts and plates to a lift condensing pressure. 80
13. In a machine of the class described, the combination of automatic means for assembling heel lifts and presser plates in alternating relation into a pile, means for subjecting the composite pile of lifts and plates to a lift condensing pressure, and means for 30 moving the composite pile of alternating lifts and plates into position for treatment by the pressure means. 85
14. In a machine of the class described, the combination of means for assembling 40 heel lifts and presser plates in alternating relation, means for subjecting the composite pile of lifts and plates to pressure, and means for transferring the lifts and plates from the assembling means to the pressure 45 means. 90
15. In a machine of the class described, the combination of a series of magazines for holding heel lifts, means for supplying presser plates in alternating relation with the magazines, means for assembling heel lifts and presser plates in alternating relation into a pile, and means for subjecting the composite pile to a lift condensing pressure. 95
16. In a machine of the class described, the combination of a series of magazines for holding heel lifts, means for supplying presser plates in alternating relation with the magazines, means for assembling heel lifts 50 and presser plates in alternating relation into piles, means for subjecting the piles of alternating lifts and plates to pressure, and means for moving the piles of lifts into position for treatment by the pressure means. 100
17. In a machine of the class described, the combination of means for supplying heel lifts and presser plates, assembling means for arranging the lifts and plates into piles with a presser plate between adjacents lifts, and means for successively subjecting the piles of composite lifts and plates to pressure. 105
18. In a machine of the class described, the combination of means for supplying heel lifts and presser plates, a support, assembling means movable for advancing piles of lifts and plates along the support, and means for simultaneously delivering a series of alternately arranged lifts and plates to said support. 110
19. In a machine of the class described, the combination of means for supplying heel lifts and presser plates, a support, assembling means movable for advancing piles of lifts and plates along the support, and means for simultaneously delivering one of the series of lifts to each of alternate piles on the support and a presser plate to each of the other piles on the support. 115
20. In a machine of the class described, the combination of means for supplying heel lifts and presser plates, a stationary support for receiving the lifts and plates, a conveyor or movable intermittently for advancing the lifts and plates along said support, and means for moving a series of lifts and plates from the supplying means and simultaneously delivering one of the series of lifts to each alternate pile on the support in each of its positions of rest and a plate to each of the other piles on the support. 120
21. In a machine of the class described, the combination of means for supplying heel lifts and presser plates, a support, assembling means movable for advancing piles of lifts and plates along the support, means for simultaneously delivering a series of alternately arranged lifts and plates to said support, and means for subjecting successive piles of alternately arranged lifts and plates to pressure. 125
22. In a machine of the class described, the combination of assembling means for assembling into piles a series of heel lifts alternating with presser plates, and means for supplying heel lifts and presser plates from opposite sides of the assembling means and arranging them in piles with a presser plate between each adjacent heel lift. 130
23. In a machine of the class described, the combination of assembling means for assembling into piles a series of heel lifts alternating with presser plates, means for supplying heel lifts and presser plates from op-

posite sides of the assembling means and arranging them in piles with a presser plate between each adjacent heel lift, and means for compressing the composite piles.

- 5 24. In a machine of the class described, the combination of a series of magazines for holding stacks of heel lifts, means for supplying presser plates, a stationary support for supporting piles composed of alternating heel lifts and presser plates, a conveyor for moving the piles along the support, and means for moving heel lifts from the magazines and presser plates from the supplying means equal in total number to the 10 number of lifts and plates in a pile and simultaneously delivering one lift to each alternate pile on the support and one plate to each of the other piles on the support.
25. In a machine of the class described, 20 the combination of a series of magazines for holding stacks of heel lifts, means for supplying presser plates, a stationary support for supporting piles composed of alternating heel lifts and presser plates, a conveyor for moving the piles along the support, means for moving heel lifts from the magazines and presser plates from the supplying means equal in total number to the number of lifts and plates in a pile and simultaneously delivering one lift to each alternate pile on the support and one plate to each of the other piles on the support, and means for subjecting the composite piles to a lift condensing pressure.
- 35 26. In a machine of the class described, the combination of a series of magazines for holding stacks of heel lifts, means for supplying presser plates, a stationary support for supporting piles composed of alternating heel lifts and presser plates, a conveyor for moving the piles along the support, means for moving heel lifts from the magazines and presser plates from the supplying means equal in total number to the number 40 of lifts and plates in a pile and simultaneously delivering one lift to each alternate pile on the support and one plate to each of the other piles on the support, means for compressing each pile, and means for successively moving the completed piles to the compressing means.

27. In a machine of the class described, the combination of means for taking a plurality of heel lifts and presser plates from sources of supply and arranging them in piles with a presser plate between adjacent lifts, means for subjecting the composite piles to compression to simultaneously condense a plurality of lifts, and means for successively separating the compressed lifts and the plates of each pile.

28. In a machine of the class described, the combination of means for taking a plurality of heel lifts and presser plates from sources of supply and arranging them in

piles with a presser plate between adjacent lifts, means for subjecting the composite piles to compression to simultaneously condense a plurality of lifts, means for successively separating the compressed lifts and 70 the plates of each pile, and means for returning the plates to the source of supply.

29. In a machine of the class described, the combination of means for taking a plurality of heel lifts and presser plates from 75 sources of supply and arranging them in piles with a presser plate between adjacent lifts, means for subjecting the composite piles to compression to simultaneously condense a plurality of lifts, means for intermittently moving the compressed piles, and means for separating the compressed lifts from the plates.

30. In a machine of the class described, 80 the combination of means for taking a plurality of heel lifts and presser plates from sources of supply and arranging them in piles with a presser plate between adjacent lifts, means for subjecting the composite piles to compression to simultaneously condense a plurality of lifts, means for intermittently moving the compressed piles, and means for separating the compressed lifts and plates as they are intermittently moved.

31. In a machine of the class described, 85 the combination of means for taking a plurality of heel lifts and presser plates from sources of supply and arranging them in piles with a presser plate between adjacent lifts, means for subjecting the composite 90 piles to compression to simultaneously condense a plurality of lifts, a carrier for removing the compressed piles from the pressure means, and means for successively removing a compressed lift and then a presser plate from the piles.

32. In a machine of the class described, 100 the combination of means for taking a plurality of heel lifts and presser plates from sources of supply and arranging them in 110 piles with a presser plate between adjacent lifts, means for subjecting the composite piles to compression to simultaneously condense a plurality of lifts, a carrier for removing the compressed piles from the pressure means, means for successively removing a compressed lift and then a plate from the piles, and means for returning the plates to the source of supply.

33. In a machine of the class described, 120 the combination of means for taking a plurality of top-lifts and presser plates from sources of supply and arranging them in piles with a presser plate between adjacent lifts, compression means for subjecting the composite piles to pressure to simultaneously condense a plurality of lifts, means for transferring the piles successively to the compression means, means for successively removing the piles from the compression 130

means after they have been compressed, and means for separating the condensed top-lifts from the presser plates.

34. In a machine of the class described, 5 the combination of means for taking a plurality of top-lifts and presser plates from sources of supply and arranging them in piles with a presser plate between adjacent lifts, compression means for subjecting the 10 composite piles to pressure to simultaneously condense a plurality of lifts, means for transferring the piles successively to the compression means, means for successively removing the piles from the compression 15 means after they have been compressed, means for separating the condensed top-lifts from the presser plates, and means for returning the presser plates to the source of supply for further use.
- 20 35. In a machine of the class described, the combination of means for taking a plurality of top-lifts and presser plates from sources of supply and arranging them in piles with a presser plate between adjacent 25 lifts, compression means for subjecting the composite piles to pressure to simultaneously condense a plurality of lifts, and means including a kicker for separating the compressed lifts and plates.
- 30 36. In a machine of the class described, the combination of means for taking a plurality of heel lifts and presser plates from sources of supply and arranging them in piles with a presser plate between adjacent 35 lifts, means for subjecting the composite piles to compression to simultaneously condense a plurality of lifts, a turret having a series of compartments for holding and transferring the composite 40 piles of lifts and plates to the compression means, and means for operating the turret.
37. In a machine of the class described, the combination of means for taking a plurality of top-lifts and presser plates 45 from sources of supply and arranging them in piles with a presser plate between adjacent lifts, compression means for subjecting the composite piles to pressure to simultaneously condense a plurality of lifts, means 50 for separating the compressed lifts and plates, and a carrier for successively presenting the composite piles of lifts and plates to the compression means and the separating means.
- 55 38. In a machine of the class described, the combination of means for taking a plurality of top-lifts and presser plates from sources of supply and arranging them in piles with a presser plate between adjacent lifts, compression means for subjecting the composite piles to pressure to simultaneously condense a plurality of lifts, means for separating the compressed lifts and plates, a carrier for successively 60 presenting the composite piles of lifts and

plates to the compression means and the separating means, and means for directing the separated lifts and plates in different paths.

39. In a machine of the class described, 70 the combination of means for assembling a plurality of heel lifts and rigid presser plates into a pile with a rigid presser plate between adjacent heel lifts, means for exerting a lift condensing pressure upon the 75 composite pile, a carrier for transferring a compressed pile from the pressure means, and means for effecting the alternate discharge of a condensed lift and presser plate.

40. In a machine of the class described, 80 the combination of means for assembling a plurality of heel lifts and rigid presser plates into a pile with a rigid presser plate between adjacent heel lifts, means for exerting a lift condensing pressure upon the 85 composite pile, a carrier for transferring a compressed pile from the pressure means, means for effecting the alternate discharge of a condensed lift and presser plate, and conveyors for conveying the discharged 90 lifts and plates from the discharging position.

41. In a machine of the class described, the combination of means for assembling a plurality of heel lifts and rigid presser 95 plates into a pile with a rigid presser plate between adjacent heel lifts, means for exerting a lift condensing pressure upon the composite pile, a turret having a plurality of openings for receiving piles of lifts and 100 presser plates, and means for turning the turret intermittently to carry uncompressed piles to the pressure means and compressed piles to a discharging station beyond the pressure means.

42. In a machine of the class described, the combination of means for assembling a plurality of heel lifts and rigid presser plates into a pile with a rigid presser plate between adjacent heel lifts, opposed compression members for compressing the composite pile of lifts and plates, means for relatively moving the compression members, a turret supported in fixed relation with one of said members and provided with 110 sockets for holding piles of lifts and plates, and means for periodically operating the turret.

43. In a machine of the class described, the combination of means for assembling a 120 plurality of heel lifts and rigid presser plates into a pile with a rigid presser plate between adjacent heel lifts, opposed compression members for compressing the composite pile of lifts and plates, means for relatively moving the compression members, a carrier for moving piles of uncompressed lifts and plates to compressing position and piles of compressed lifts and plates away from compressing position, and a 125 130

support over which the carrier is moved and which has openings therethrough for the separate discharge of compressed lifts and plates.

- 5 44. In a machine of the class described, the combination of means for assembling a plurality of heel lifts and rigid presser plates into a pile with a rigid presser plate between adjacent heel lifts, opposed com-
10 pression members for compressing the composite pile of lifts and plates, means for relatively moving the compression members, a carrier for moving piles of un-
15 compressed lifts and plates to compressing position and piles of compressed lifts and

plates away from compressing position, a support over which the carrier is moved and which has openings therethrough for the separate discharge of compressed lifts and plates, and doors for controlling said 20 openings.

In testimony whereof I, the said ALBERT E. HUDSON, have signed my name to this specification.

ALBERT E. HUDSON. 25

In testimony whereof I, the said WILLIAM C. WILLSON, have signed my name to this specification.

WILLIAM C. WILLSON.
